United States Patent Office

Des. 193,364
Patented Aug. 7, 1962

193,364

PRINTER ACCESSORY FOR A FILM READER

Norman J. Rosenburgh and Ralph M. Vigna, both of
400 Plymouth Ave. N., Rochester, N.Y.

Filed Dec. 18, 1961, Ser. No. 67,931

Term of patent 14 years

(Cl. D61—1)

Fig. 1

FIG. 1 is a perspective view of a printer accessory for a film reader showing our new design; and

FIG. 2 is a front perspective view taken from the rear thereof.

The broken line showings of a representative film reader in FIG. 1 and FIG. 2 is for illustrative purposes only.

We claim:

The ornamental design for a printer accessory for a film reader, as shown and described.
